DESIGN FOR A SERVICE STATION

Walter D. Teague, Forest Hills, N. Y., assignor to
The Texas Company, New York, N. Y., a corpo-
ration of Delaware

Application October 5, 1935, Serial No. 58,846

Term of patent 14 years

To all whom it may concern:

Be it known that I, Walter D. Teague, a citizen of the United States, residing at Forest Hills, in the county of Queens and State of New York, have invented a new, original, and ornamental Design for a Service Station, of which the following is a specification, reference being had to the accompanying drawings, forming part thereof, in which—

Fig. 1 is a view in perspective of a service station embodying my design.

Fig. 2 is another view in perspective of the same service station with the top portion removed.

I claim:

The ornamental design for a service station, as shown.

WALTER D. TEAGUE.
